UNITED STATES PATENT OFFICE.

CLARENCE E. SLYE, OF SANDWICH, ILLINOIS.

GARMENT-HANGER.

1,086,863.

Specification of Letters Patent. Patented Feb. 10, 1914.

Application filed May 26, 1910. Serial No. 563,649.

To all whom it may concern:

Be it known that I, CLARENCE E. SLYE, citizen of the United States, residing at Sandwich, in the county of Dekalb and 5 State of Illinois, have invented certain new and useful Improvements in Garment-Hangers; and I do hereby declare the following to be a full, clear, and exact description of the invention, such as will enable 10 others skilled in the art to which it appertains to make and use the same.

This invention relates to a novel construction in a collapsible garment hanger, the object being to provide a simple, efficient, 15 light device of this character which when collapsed occupies a very limited space and which may be readily and easily expanded for the purpose of hanging garments thereon, and consists in the features of construction 20 and combinations of parts hereinafter fully described and claimed.

In the accompanying drawings illustrating this invention: Figure —1— is a top plan view of a garment hanger constructed 25 in accordance with my invention showing the same collapsed and folded. Fig. —2— is a bottom plan view of the same showing it in the same position. Fig. —3— is a side elevation of the same showing the suspension hook elevated preparatory to expanding the hanger proper. Fig. —4— is a view 30 similar to Fig. —2— showing the end members of the hanger moved to their primary outer positions preparatory to expanding 35 the entire hanger. Fig. —5— is a top plan view of the hanger showing the same expanded ready to receive garments such as coats, vests or ladies' waists, and nether garments such as skirts and trousers. Fig. —6— is a side elevation of the same showing 40 a pair of trousers suspended therefrom. Fig. —7— is a fragmentary detail sectional view on the line 7—7 of Fig. —1—. Fig. —8— is a detail sectional view on the line 45 8—8 of Fig. —2—. Fig. —9— is a detail section on the line 9—9 of Fig. —8—.

The principal object of my invention is to provide a garment hanger for travelers' use which is light, strong, durable and efficient 50 and which when collapsed occupies a very small space so as to enable the same to be easily carried in a pocket, and which, when fully expanded, will be of sufficient length to extend into the upper ends of the sleeves 55 of a coat to properly support the latter.

A further object of the invention is to

provide a collapsible hanger which when expanded presents a curved supporting surface corresponding at its end portions substantially with the inclinations of the 60 shoulder portions of a body garment such as a coat or a lady's waist and which furthermore is equipped with means for simultaneously suspending therefrom nether garments such as trousers or skirts so that a single hanger will be adapted for the suspension 65 of an entire suit.

My said hanger consists essentially of a body portion including a plurality of pairs of lazy-tong levers 1 and 2, each pair thereof being pivotally secured together midway between their ends and joined to contiguous pairs at their ends by means of rivets in the ordinary and well-known manner. The middle pair 1 of said lazy-tong levers is pivotally secured together midway between its ends by means of a member 3 having a shank passing through the central openings in said levers and through a washer 4 disposed below the same, the latter being provided with a counter-sunk opening into which the end 70 of said shank is expanded, as particularly shown in Figs. —8— and —9—. The upper end of said member 3 constitutes an eye through which the lower end of the rod 5 is 75 passed, the latter being bent around the upper portion of said member 3 to pivotally secure the same thereto. At its free end said member 3 is provided with a recess 6, shown in dotted lines in Fig. —1— and in 80 full lines in Fig. —6—, in which the enlarged upper end of a rivet 7 is adapted to be received, as will be hereinafter more particularly described. Pivotally secured to said rod 5 adjacent the free end portion 85 thereof is a hook 8 similarly equipped at the other end of its shank and beyond the point of pivotal connection therewith with said rod 5 with a recess 9 similarly adapted to receive the upper end portion of said rivet 7, 90 100 as will be hereinafter more particularly described.

To the free ends of each of the lazy-tong levers 2 there are secured curved members 10 and 11 respectively, at one end of each of the latter, the same being pivotally secured together at their other ends. Said member 11 is provided at the last-named end with a projection 12 extending toward the first-named end thereof, the same being bent in 110 ogee-curved form and depressed to project below the plane of the member 11 for rea-

sons to be hereinafter more fully pointed out. The distance between the pivotal connections 13 of said members 10 and 11 with the lazy-tong levers 2 and their pivotal connections 14 with each other is very slightly greater than the distance between the said pivotal connections 13 and the pivotal connections 15 of the tongs 2 with each other. All of the said lazy-tong levers are curved 10 slightly so that when expanded, as shown in Fig. —5—, the hanger formed thereby will present a properly curved supporting surface for the shoulder portions of the garments hung upon the same. When in this 15 position the said projections 12 extend at their free ends toward the axis of suspension of the hanger and constitute hooks for the reception of suitable loops on nether garments, such as trousers or skirts, for suspending the latter from said hanger.

In Fig. —6— I have shown a pair of trousers suspended from said projections 12 by inserting the same through the loops of the suspenders secured to the front portions 25 of the trousers, the hook 8 and rod 5 being inserted through the loop of the suspenders secured to the rear portion of the trousers, the latter being thus suspended at three points. Ladies' skirts may be similarly equipped with suitable loops made of 30 tape, or the like, adapted to be similarly suspended for hanging the skirt from my said device.

The lazy-tong levers enable the device to be contracted to a very small width in one direction but of increased depth in the manner common to this class of devices. The said curved end members 10 and 11, however, will take up a little more space than 40 the straight lazy-tong levers when the device is folded and in order to decrease the total width of the collapsed device as far as possible and furthermore to hold the same relatively securely in its collapsed position the same are sprung inwardly relatively to the ends of the collapsed lazy-tongs. Fig. —4— shows the said end members 10 and 11 in the position primarily normally occupied thereby when the said 50 hanger is collapsed. As previously stated the distance from the pivots 13 to the pivots 14 is greater than the distance from the pivots 13 to the pivots 15. Hence to contract the device to its utmost limits it becomes necessary to spring the pivots 14 past 55 the pivots 15. The curvature of said members 10 and 11 readily permits this to be accomplished and when accomplished the ends of the members 11 contiguous to the pivots 14 will be thrown into contact with 60 each other at a point substantially in axial alinement with the pivotal connection of the shank of the member 3 with lazy-tongs 1. In order to prevent the said members 11 65 from being readily sprung outwardly and to

insure the device remaining collapsed more securely than would otherwise be the case the said members 11 are provided with projections 16 having opposing ogee-curved surfaces adapted to contact with and hook into each other and thus engage each other somewhat in the manner of a spring latch. When so engaged the said overlapping projections 16 will cover the said washer 4, the latter being then disposed between the opposing ends of the respective members 10. Before the device has been so collapsed the hook 8 is turned on its pivot to invert the same relatively to the rod 5 and the latter is then turned upon its pivotal connection 70 with the member 3 so as to lie flat upon one end portion of one of said lazy-tongs 1. The said rivet 7 pivotally connecting the said end of said lazy-tong 1 with one end of one of said lazy tongs 2, previously referred 75 to, is now received at its projecting end portion in the said recess 6 in said rod 5 and in the recess 9 in the shank of the hook 8, said respective recesses 6 and 9 being opposed to each other and engaging the said rivet from 80 opposite sides. In order to prevent confusion the pivotal connection of said rod 5 with said member 3 is preferably so made in any suitable manner as to prevent said rod 5 from being turned on said pivot in a 85 direction to oppose the convex face thereof to a convex face of one of said lazy tongs, as it will be obvious that if this were possible it might result in the user attempting 90 to distort said rod in order to cause same to lie flat upon said lazy-tong. To this end, in the instance illustrated, the end portion of said member 5 passing through the loop of said member 3 is bent to a right angle and is 95 then bent over at its free end to embrace the upper part of said loop thus providing a 100 projection 17 which is adapted to contact with the lower portion of said loop, thus preventing the same from swinging in one direction but permitting it to swing freely 105 in the opposite direction. Thus it is assured that the concave face of said rod 5, which corresponds in curvature substantially with the curvature imparted to the 110 lazy-tongs 1, will oppose the convex face of the latter so that when completely folded or 115 collapsed the device will have the thickness only of the several thicknesses of metal of the tongs, rod, hook and end members 10 and 11 while its width will be equal to the 120 sum of the widths of said several lazy-tong levers plus the added depth imparted by the curvature of said end members 10 and 11 and its greatest dimension will be equal to the full length of one of said lazy-tong 125 levers.

My said device is very simple as will be readily seen and may be made of very light and strong material so as to fully answer the purposes for which it is intended.

I claim as my invention:

1. A device of the kind specified, comprising a body-portion consisting of a plurality of pairs of lazy-tong levers pivotally secured together, and a pair of links at each end of said body portion, each of said links secured at one end to the outer end of one of the lazy-tong levers of an end pair and pivotally secured together at their other ends, said links being curved between their ends and relatively disposed so that the concave edges thereof are opposed when said body-portion is extended and constituting extensions for said body portion and shoulder supports for a garment.
2. A device of the kind specified, comprising a body-portion consisting of a plurality of pairs of lazy-tong levers pivotally secured together, and a pair of links at each end of said body portion, each of said links secured at one end to the outer end of one of the lazy-tong levers of an end pair and pivotally secured together at their other ends, said links being curved between their ends and relatively disposed so that the concave edges thereof are opposed when said body-portion is extended and constituting extensions for said body portion and shoulder supports for a garment, and a projection at one end of one link of each pair adapted when said body-portion is extended, to project from the extreme ends thereof inwardly into the opening formed between said links.
3. A device of the kind specified comprising a body portion including a pair of lazy-tong levers, a suspending device secured to the pivot thereof, pairs of lazy-tong levers disposed at opposite ends of said first-named pair and pivotally secured at one end each to the respective ends of the latter, two pairs of links pivotally secured at one end of each to the free ends of said respective last-named pair of said levers and pivotally secured together at their other ends, all of said levers and said links being curved between their ends in a plane extending transversely to the axes of all of said pivots and providing a completed structure presenting a continuous convex supporting surface extending from end to end of the body portion and having enlarged end portions.
4. In a device of the kind specified a body portion including a collapsible lazy-tong lever structure affording a continuous convex supporting surface for garments extending from end to end of the body portion, the garment adapted to rest upon said body portion over its entire length.
5. A device of the kind specified comprising a body-portion consisting of a collapsible lazy-tong lever structure affording a continuous convex supporting surface for garments extending from end to end of said body portion, and collapsible substan-
- tially elliptical loops pivotally secured to said body portion at the ends thereof, said loops of greater width than said body portion when the latter is fully extended.
6. A device of the kind specified comprising a body-portion consisting of a collapsible lazy-tong lever structure terminating at its ends, when extended in substantially elliptical loops of greater width than said body portion and constituting continuations thereof, said body portion affording a continuous convex supporting surface for garments.
7. In a device of the kind specified, a body portion including a collapsible lazy-tong lever structure consisting of levers curved between their ends and relatively pivotally movable in a spherical plane, said structure when expanded affording a continuous convex supporting surface for garments extending from end to end of the body portion, a pair of links pivotally connected with each other at one end disposed at either end of said structure and pivotally secured at their other ends to the said lazy-tong lever structure at the ends of the latter, said links constituting terminals for said structure.
8. In a device of the kind specified, a body portion including a collapsible lazy-tong lever structure consisting of levers curved between their ends and relatively pivotally movable in a spherical plane, said structure when expanded affording a continuous convex supporting surface for garments extending from end to end of the body portion, a pair of links pivotally connected with each other at one end disposed at either end of said structure and pivotally secured at their other ends to the said lazy-tong lever structure at the ends of the latter, said links constituting terminals for said structure.
9. In a device of the kind specified, a collapsible lazy-tong lever structure consisting of levers curved between their ends and relatively pivotally movable in a spherical plane, said structure when expanded affording a continuous convex supporting surface for garments, a pair of links pivotally connected with each other at one end disposed at either end of said structure and pivotally secured at their other ends to the said lazy-tong lever structure at the ends of the latter, said links constituting terminals for said structure, and being oppositely curved to project laterally beyond the side edges of said structure when the latter is fully expanded.
10. In a device of the kind specified, a

collapsible lazy-tong lever structure consisting of levers curved between their ends and relatively pivotally movable in a spherical plane, said structure when expanded affording a convex supporting surface for garments, a pair of links pivotally connected with each other at one end disposed at either end of said structure and pivotally secured at their other ends to the said lazy-tong lever structure at the ends of the latter, said links constituting terminals for said structure, the distance between the pivot of said respective links with each other and their pivotal connections with the end levers of said lazy-tongs being greater than the distance between the last-named pivots and the nearest adjacent pivotal connection between a pair of said lazy-tongs, said first-named pivots being adapted to be sprung past a line of dead center passing through the second-named pivots when said structure is collapsed.

11. In a device of the kind specified, a collapsible lazy-tong lever structure consisting of levers curved between their ends and relatively pivotally movable in a spherical plane, said structure when expanded affording a convex supporting surface for garments, a pair of links pivotally connected with each other at one end disposed at either end of said structure and pivotally secured at their other ends to the said lazy-tong lever structure at the ends of the latter, said links constituting terminals for said structure, the distance between the pivot of said respective links with each other and their pivotal connections with the end levers of said lazy-tongs being greater than the distance between the last-named pivots and the nearest adjacent pivotal connection between a pair of said lazy-tongs, said first-named pivots being adapted to be sprung past a line of dead center passing through the second-named pivots when said structure is collapsed, and a projection on one link of each pair having an ogee curved surface, said surfaces being opposed and sprung into engagement with each other when said links are sprung past said line of dead center, substantially as described.

12. In a device of the kind specified, a collapsible lazy-tong lever structure presenting a convex supporting surface lying in a spherical plane, a folding suspending device secured to said structure centrally thereof and comprising a hook, and a link

pivotedly secured thereto adjacent one end and having pivotal connection with said structure at its other end.

13. In a device of the kind specified, a collapsible lazy-tong lever structure presenting a convex supporting surface lying in a spherical plane, a folding suspending device secured to said structure centrally thereof and comprising a member secured to said structure, a link having hinged connection therewith, and a hook pivotally connected with said link.

14. In a device of the kind specified, a collapsible lazy-tong lever structure presenting a convex supporting surface lying in a spherical plane, a folding suspending device secured to said structure centrally thereof and comprising a member secured to said structure, a link having hinged connection therewith, there being a recess in the free end portion of said link, a hook equipped with a shank pivotally connected between its ends with said link between the ends of the latter, there being a recess in the free end of said shank adapted to oppose the recess in said link, and a projection on said structure adapted to be engaged in said respective recesses to hold said structure when folded, substantially as described.

15. In a device of the kind specified, a collapsible lazy-tong lever structure presenting a convex supporting surface lying in a spherical plane, a folding suspending device secured to said structure centrally thereof and comprising a member secured to said structure, a link having hinged connection therewith, there being a recess in the free end portion of said link, a hook equipped with a shank pivotally connected between its ends with said link between the ends of the latter, there being a recess in the free end of said shank adapted to oppose the recess in said link, and a projection on said structure coincident with one of the pivotal connections between contiguous pairs of said lazy-tong levers adapted to be engaged in said respective recesses to hold said structure when folded, substantially as described.

In testimony whereof I have signed my name in presence of two subscribing witnesses.

CLARENCE E. SLYE.
